HYPO JET AMPOULE

Robert Pauli Scherer, Detroit, Mich., assignor to
 R. P. Scherer Corporation, Detroit, Mich., a
 corporation of Michigan

Application May 14, 1949, Serial No. 93,282

2 Claims. (Cl. 128—272)

1

This invention relates to a hypodermic jet injection ampule. Injection ampules of the type to which this invention pertains are designed to contain a dosage of liquid medicament, which dosage is adapted to be ejected from the ampule by means of a hypo jet injector such as disclosed and claimed in my copending application, Serial No. 94,579, filed May 21, 1949. In said disclosure the jet ejected from the ampule passes through a minute jet orifice in the wall of the ampule in such manner and under a sufficiently high pressure to result in the necessary velocity to produce a penetrating jet that opens a channel through the skin and the underlying tissues of a human being or animal for accomplishing subcutaneous injection of a liquid medicament or the like to a closely controlled depth without the use of the conventional hypodermic needle. Injections of this type may be characterized as jet injections, hypo jet injections, or jet therapy, the method for which is fully disclosed and claimed in my copending application, Serial No. 77,517, filed February 21, 1949. Jet injections represent a relatively new development in the field of parenteral therapy and are approached to some extent by the disclosures in the following Lockhart patents: 2,322,244, June 22, 1943; 2,322,245, June 22, 1943; 2,380,534, July 31, 1945; 2,398,544, April 16, 1946.

My jet injection ampule is designed to provide for consistently successful and complete injections of the liquid contents of the ampules through the epidermis to any desired subcutaneous level therebeneath.

In experimenting with jet injections from ampules I have found that difficulty is often encountered and wastage of the liquid medicament is not infrequent particularly if quantities of liquid in excess of about $\frac{1}{50}$ cc. are to be injected. Even though the operator endeavors to stretch the skin of the patient taut across the point at which the injection is to be made, an instantaneous and clear-cut piercing of the skin by a high-pressure, high velocity penetrating jet projected from the ampule frequently does not initially occur and liquid is wasted on the outer surface of the skin such as would be the case if liquid were sprayed through the air toward the skin.

With ampules having flat areas of appreciable extent surrounding the ampule orifice there was a tendency for drops of the liquid from the ampule to collect in a pool between the skin of the patient and the end of the ampule about the orifice. There was also a tendency for this pool to increase in size upon the delivery of liquid from the ampule with the result that the skin was

5 lubricated thereby and the end of the ampule "skidded" over the skin of the patient especially if the dosage was larger than $\frac{1}{50}$ cc. Larger dosages required larger springs in the injectors to expel the additional liquid and this aggravated the condition.

10 Due to the high velocity of the liquid stream discharging from the ampule orifice a linear cut in the skin of the patient marking the extent of the skid would frequently occur with resulting pain, whereas a proper jet injection is either painless or merely on the threshold of pain. In order to avoid prohibitive concentration of the liquid medicament I have found it desirable to inject as much as 1 cc.

15 At the same time it is imperative that assured accuracy as to quantity of liquid actually injected is obtained.

20 My improved jet injection ampule is so shaped at its discharge end surrounding the jet orifice that when the discharge end is pressed against the skin of the patient who is to receive an injection, the portion of the skin which extends across the jet orifice is stretched taut thereover and actually bulges into the orifice due to subcutaneous pressure opposing the pressure of the ampule against the skin. An effective hydraulic seal is thereby had against the edge of the jet orifice even when liquid is present around the jet orifice. 25 Accordingly the injection is easily accomplished; there is instantaneous breakthrough of the skin upon impact of the high pressure penetrating jet therewith, the injection in its initial stage as well as during the follow-through is accomplished without wastage on the outer surface of the skin and the entire dosage of liquid is properly injected to a hypodermic position at the desired subcutaneous level without danger of any skidding when my improved ampule is used in connection with 30 my hypo jet injector.

35 Another important advantage of ampules provided with jet orifice discharge ends shaped as herein set forth is that the tendency for a pool of liquid from the ampule to collect between the skin and the discharge end of the ampule during injection is completely eliminated and the possible skidding of the end of the ampule with the attendant slitting of the patient's skin is also 40 eliminated.

45 Still another important consideration in the design of an ampule is the shape of the jet discharge orifice to reduce turbulence of the liquid just before it leaves the ampule and thereby secure a jet that will remain in true jet form for maximum penetrating and channel open-

ing effect. The orifice must be carefully formed and streamlined so as to eliminate any chance for turbulence as the jet issuing therefrom has a velocity in the neighborhood of six hundred miles per hour. Any turbulence accordingly disturbs the jet so that its columnar form is not maintained and accordingly it is obviously important to streamline the orifice and the adjacent inner surface of the ampule leading from its interior to the orifice and in fact lap or polish its surface to reduce turbulence to as close to absolute minimum as possible.

With these and other objects in view, my invention consists in the construction, arrangement and combination of the various parts of my ampule whereby the objects contemplated are attained, as hereinafter more fully set forth, pointed out in my claims and illustrated in the accompanying drawings wherein:

Figure 1 is a perspective view of a hypodermic jet injection ampule embodying my invention and showing one form that it may take;

Figure 2 is a greatly enlarged sectional view therethrough showing the ampule in contact with the skin of the patient, filled with medicament and having a follower backed by a plunger of the hypo jet injector described in my above first mentioned copending application;

Figure 3 is a more greatly enlarged sectional view of the discharge end of the ampule in contact with the skin;

Figure 4 is similar to Figure 3 with the penetrating jet beginning to issue from the ampule and passing through the skin, and the tissues that underlie the skin;

Figures 5, 6 and 7 show sectional views of modified forms of the discharge end of the jet ampule;

Figure 8 is a sectional view through another modified shape of ampule; and

Figure 9 is a sectional view on the line 9—9 of Figure 8.

On the accompanying drawing I have used the reference character A to indicate my jet injection ampule in general. It is illustrated in Figures 1 and 2 as having a cylindrical wall 10, one end being somewhat convergently restricted as at 12 and rounded or bullet shaped as at 14, and the other end being open. The rounded end 14 may be somewhat flattened as at 15 to smooth the metal where it contacts with the skin. A shoulder 13 is provided between the cylinder 10 and the restricted part 12 to facilitate holding the ampule in a hypo jet injector, the shoulder 13 engaging a shoulder in the injector.

The rounded end 14 has therein a jet discharge orifice 16 which is preferably between .002" and .005" in diameter. The lower end of this orifice has substantially parallel sides but the upper half is rounded or streamlined as indicated at 18 so that the interior surface of the jet orifice blends smoothly with the inner surface of the ampule A. The orifice 16 and the surface indicated at 18 must be accurately formed and very smooth, lapping or polishing being preferable to make the surface smooth enough to prevent any turbulence in the jet that issues from the jet orifice when the injector is operated.

Injection ampules illustrated in the Lockhart patents above listed are provided with flat lower ends or with lower ends which are even countersunk. In most cases the lower ends of the ampules illustrated in the patents were not intended to be pressed against the skin of the patient during the injection but were intentional-

ly held spaced therefrom at the time of injection.

In the ampule I disclose, the discharge end is intended to be firmly pressed against the skin 5 of the patient at the point of injection and that portion of the ampule which surrounds the jet orifice is so shaped that the skin will be stretched taut across the orifice with the edge of the orifice effecting a hydraulic seal against the skin.

10 In Figure 2, I illustrate the skin consisting of the epidermis or cuticle 20 and the corium or dermis 22 beneath which the subcutaneous fat cells are illustrated at 24, the fascia at 25 and the muscle at 27. When the ampule is pressed 15 against the epidermis 20 it compresses the fat cells and dents the skin as illustrated with the skin actually bulging into the jet orifice 16 (see particularly Figure 3). The rounded or bullet shape of the ampule end results in the epidermis 20 being progressively more tightly engaged with the ampule as the edge of the orifice is approached, greatest compression being had at the edge of the orifice and consequently this is the point of best hydraulic sealing.

25 The ampule itself may be any desired shape as long as the portion thereof adjacent the orifice 16 is similar to a protuberance as distinguished from a more or less flat surface unless the flat surface is no larger in proportion to the orifice than illustrated in Figure 6 considering the orifice exaggerated about 2 to 1.

30 In Figure 2, I illustrate liquid 26 within the ampule A which may be a liquid medicament behind which a follower 28 of rubber or the like is provided. This follower is adapted to be forced downwardly in the ampule A by a plunger 30 as shown in my hypo jet injector application.

35 The plunger 30 is propelled by suitable means such as a spring and produces relatively great hydraulic pressure on the liquid 26 to project it from the jet orifice 16 in the form of a true jet as indicated at 26a in Figure 4. The pressures involved are high, being in the thousands of pounds per square inch range and the resulting jet velocity is high, approaching the speed of sound. With the jet opening 16 being only about .003" in diameter however the actual pressure against the skin is relatively minute as the area is only .000009 and when the jet penetrates through the skin and into the underlying tissues as illustrated in Figure 4 it is usually scarcely noticed by the patient because of the absence of pain or at most because of the existence of only slight pain.

40 45 50 55 The ampule end may be rounded as illustrated in Figure 5 or bullet shaped as in Figure 6 which is still better from the standpoint of insuring a proper hydraulic seal to confine the jet 26a so there is no leakage on the surface of the skin, and to insure that all the liquid from the ampule 60 can be injected into the passageway opened by the initial penetrating jet.

65 It will be noted that the peripheral edge of the jet orifice 16 is in cross section an acute angle in Figures 5 to 8 for obtaining a more effective hydraulic sealing action right at the edge of the orifice. The end of the ampule may present a less sharp angle at this point by being flattened as in Figures 2, 3 and 4 or semi-circular in shape as shown in Figure 5 instead of bullet shaped as in Figures 6, 7 and 8 or slightly flat as at 34 in Figure 6 and as at 15 in Figure 3.

70 75 The complete injection operation takes about a second's time and in normal injections I have found it best to wait about another second before

removing the ampule from contact with the skin in order to insure that all the liquid goes into the jet opened channel of the tissues. Thereafter these tissues reclose the channel which was formed by the penetrating jet that acted as a means to expand the channel in opposition to the elasticity of the tissues.

Figure 7 shows a slight modification wherein a protuberance 36 is formed around the jet orifice 16 and accordingly serves as a means to effect the required hydraulic seal regardless of the shape of the remaining portion of the ampule. Figure 8 illustrates a similar protuberance 36a at a different location on the ampule. This type permits use of the ampule at places on the body where it is not possible to extend the ampule and its holder (the hypo jet injector) at right angles to the injection location. This type is particularly adaptable for dental injections as quite often it is not possible to position the injector at right angles to the point of the gum at which an injection is to be made.

The several modifications illustrate possibilities for the provision of a hypodermic jet injection ampule that is successfully operable for the intended purpose. It is highly important to reduce the effect of the pressure behind the liquid by reducing the area of the skin acted upon to substantially the minimum and of course the minimum is the area represented by only the jet opening 16, that is, its edge. This is true even when the flat ends 15 and 34 shown in Figures 3 and 6 are provided because of the way the epidermis bulges into the orifice if the flat ends are not of much greater proportional area than illustrated. The results obtained with my ampule make the difference between a successful injection at every injection operation and injections that are sometimes unsuccessful and result in the operator not knowing how much of the injection actually took place as well as the possibility of slitting the patient's skin as the result of a "skid."

Ampules of the character disclosed may be made of suitable metal, or formed of plastic materials or glass if made of greater wall thickness to provide the necessary strength to resist the high pressures generated.

It will be apparent from the foregoing disclosure that when any one of my ampules is held tightly against the skin a hydraulic seal is effected between the edge of the jet orifice and the skin as to confine the jet to only that portion of the skin that spans the jet orifice, thus minimizing the size of the puncture in the skin made by the penetrating action of the jet and at the same time eliminating the possibility of a skid of the ampule resulting in a slit or multiple injection through the skin. Some skin is loose and flabby but with ampules shaped as illustrated good hydraulic sealing can be effected in order to provide the proper type of hydraulic seal be-

tween the orifice edge and the body of the patient to insure proper jet operation.

This also insures that after the penetrating jet has ceased a lower pressure follow-through jet may continue with assurance that the liquid introduced by the follow-through jet will enter the channel initially opened by the penetrating jet. The result is assured dosage quantity by a method which is reliable and by a hypo jet injector, the operation of which is relatively simple.

Some changes may be made in the construction and arrangement of the parts of my ampule without departing from the real spirit and purpose of my invention, and it is my intention to cover by my claims any modified forms of structure or use of mechanical equivalents which may be reasonably included within their scope.

I claim as my invention:

1. A jet injection ampule comprising a cylinder open at one end to receive a plunger and provided at the opposite end with a cylinder closing wall having a jet orifice therethrough, a protuberance extending from the outer surface of said cylinder closing wall and surrounding said jet orifice, liquid in said cylinder, and a follower slidale within said cylinder to eject said liquid through said jet orifice.

2. A jet injection ampule comprising an elongated cylinder open at one end to receive a plunger and provided at the opposite end with a cylinder closing wall having an axial jet orifice therethrough, a centrally located protuberance extending from the outer surface of said cylinder closing wall and surrounding said jet orifice, liquid in said cylinder, a follower slidale within said cylinder to eject said liquid through said jet orifice under high pressure to produce a penetrating jet capable of passing through the skin of a human being and penetrating subcutaneously therebeneath, said protuberance surrounding said jet orifice being adapted for pressure contact with the skin so that the skin will be stretched over said orifice and bulge into it for sealing the peripheral edge of said orifice relative to the skin.
